UNITED STATES PATENT OFFICE.

JOHN LACKNER, OF NEW YORK, N. Y.

BUFFER FOR EXPLOSIVE SHELLS.

1,331,510.

Specification of Letters Patent. Patented Feb. 24, 1920.

Application filed September 28, 1918. Serial No. 256,075.

To all whom it may concern:

Be it known that I, JOHN LACKNER, a citizen of the United States, and a resident of the city of New York, Flushing, borough 5 of Queens, in the county of Queens and State of New York, have invented a new and Improved Buffer for Explosive Shells, of which the following is a full, clear, and exact description.

10 The object of the invention is to provide a new and improved flexible and pliable article of manufacture for use, for instance, as a buffer, gromet or a fender on explosive shells to permit of safely stacking such shells and 15 prevent accidental premature explosions thereof. Another object is to permit of using the article of manufacture for various purposes, the article having the desired resilient and pliable qualities. Another 20 object is to permit of providing an article of this flexible and pliable character, which is cheap to manufacture, exceedingly durable and not liable to open up or break when in use.

25 With these and other objects in view, the invention consists of certain novel features of construction, as hereinafter shown and described and then specifically pointed out in the claim.

30 For the purpose of illustrating my invention, I have shown in the accompanying drawings one form thereof which is at present preferred by me, since the same will be found in practice to give satisfactory and 35 reliable results, although it is to be understood that the various instrumentalities of which my invention consists can be variously arranged and organized and that my invention is not limited to the precise arrangement and organization of these instrumentalities as herein shown and described.

40 A practical embodiment of the invention is represented in the accompanying drawings forming a part of this specification, in 45 which similar characters of reference indicate corresponding parts in all the views.

Figure 1 is a perspective view of a tubular piece of knitted fabric forming the blank for making the article of manufac- 50 ture;

Fig. 2 is a sectional side elevation of the same partly rolled up;

Fig. 3 is a perspective view of the article of manufacture;

Fig. 4 is an enlarged cross section of the 55 same on the line 4—4 of Fig. 3; and

Fig. 5 is an enlarged side elevation showing the means for fastening the edge of the outermost layer to the body.

The blank 10 from which the article of 60 manufacture is made is a tubular piece of knitted textile fabric of an interior diameter corresponding to the inner diameter of the article to be made. The blank 10 is rolled up outwardly beginning at one edge 65 to provide an annular body 11 formed of superimposed annular layers of the textile material, as plainly indicated in Figs. 2, 3 and 4. The outer edge of the outermost layer has its loops 12 engaged by a tying 70 cord 13 engaging loops or stitches of the preceding layer so as to securely fasten the outer edge of the outermost layer to the body 11 to prevent the layers from accidentally unrolling. The ends of the tying cord 13 75 are knotted together to fasten the edge in place on the body (see Fig. 5). It will be noticed that the annular body 11 is cylindrical in cross section and as it is formed of superimposed layers of a knitted textile 80 fabric having its edge secured by a tying cord which is reeved through the loops on the outer edge of the body and juxtaposed loops on the adjacent convolution of the roll, it is evident that the desired resiliency 85 is had not only throughout the body but through its pliable fastening means and the body and its fastening means being flexible and pliable throughout can somewhat stretch in the direction of its length to insure a close fit on a shell or other article 90 on which it is to be used as a buffer, fender or gromet. It will further be noticed that the article can also be used for various purposes, and I do not limit myself to any particular use that may be made of the article. 95

Although a knitted blank is prepared I do not limit myself to such textile material as a braided tubular blank or a loosely woven tubular blank may be used. Although the blank is shown and described as rolled up outwardly it is evident it may be rolled up inwardly, but in this case the diameter of the tubular blank must be in 100

excess of that of the article on which it is to be used. In devices of this character it is essential for the purposes intended that not only the body of the device be flexible and pliable but that the fastening means which secures the juxtaposed edges be equally flexible and pliable and to this end, I employ the tying cord 13, which is reeved through the loops on the outer edge of the body and juxtaposed loops on the adjacent convolution of the roll. By this expedient the completed article is rendered very flexible and pliable not only externally and internally but throughout every portion of its area, so that when the device is employed as a fender on explosive shells and for the other purposes intended, its inherent flexible and pliable qualities throughout its entire area will render it particularly applicable for the purposes intended.

In this respect my novel device is differentiated from the British patent to Cuthbertson of 1911, with which I am familiar, since in that device the surface of the tube before rolling is treated with adhesive material, so that the folds or meeting portions stick or adhere together, so as to form one concrete mass, which obviously does not possess the pliability and flexibility of my device. I am also aware that it has been proposed to fasten separate portions of a stocking together by a thread passing through loops therein but such a device is

not adapted to the purposes of my invention and to none of the devices of the prior art do I herein make my claim.

It will now be apparent that I have devised a novel and useful buffer or like article of manufacture which embodies the features of advantage enumerated as desirable in the statement of the invention and the above description, and while I have, in the present instance, shown and described a preferred embodiment thereof which will be found in practice to give satisfactory and reliable results, it is to be understood that the same is susceptible of modification in various particulars without departing from the spirit or scope of the invention or sacrificing any of its advantages.

Having thus described my invention, I claim as new and desire to secure by Letters Patent:

A protecting means for explosive shells and like articles, comprising an endless ring constructed from a single tubular blank of loosely looped textile material, and having a rolled up body comprising a roll of superimposed volutions, the edge of said roll and the body having loops thereon juxtaposed to each other, and a pliable tying cord reeved through the juxtaposed loops, whereby a body is produced which is flexible and pliable.

JOHN LACKNER.
